UNITED STATES PATENT OFFICE.

JOSEPH J. O'BRIEN, OF GALVESTON, TEXAS.

VEHICLE-SPRING LUBRICATOR.

Application filed November 10, 1922. Serial No. 600,021.

To all whom it may concern:

Be it known that I, JOSEPH J. O'BRIEN, a citizen of the United States, residing at Galveston, in the county of Galveston and 5 State of Texas, have invented new and useful Improvements in Vehicle-Spring Lubricators, of which the following is a specification.

The object of my said invention is the 10 provision of an efficient vehicle spring lubricator adapted to cause lubricant to seep to the under center of each spring leaf with a view to thoroughly lubricating the entire under surface of the leaf, and one which 15 does not have to be frequently refilled with lubricant.

To the attainment of the foregoing the invention consists in the improvement as hereinafter described and definitely claimed.

20 In the accompanying drawings, forming part of this specification:

Figure 1 is an elevation of my novel lubricator with the shims omitted.

Figure 2 is an elevation taken at right 25 angles to Figure 1.

Figure 3 is a vertical section taken in the plane indicated by the line 3—3 of Figure 2.

Figure 4 is a vertical section taken in the 30 plane indicated by the line 4—4 of Figure 3.

Figure 5 is a plan view of the absorbent stirrup comprised in the lubricator.

Figure 6 is a plan view of one of the shims.

35 Figure 7 is a detail elevation of one of the side clamping plates of the lubricator.

Figure 8 is a plan view of the bottom plate of the lubricator.

Similar numerals of reference designate 40 corresponding parts in all of the views of the drawings.

The spring leaves are numbered 1, and in accordance with my invention a flanged box 2 is superimposed on the series of leaves 45 1, the said box 2 being equipped at its under side with a layer 3 of felt or other appropriate material, and being equipped at its upper side with a filling cup 4. The flanges 50 5 of the box are apertured for the passage of the headed and threaded bolts 6, the said bolts 6 being arranged in pairs to also pass through the apertures 7 in the bottom plate 8, which plate 8 is also provided with slots 9 for the passage of the downwardly reaching arms of the side clamping plate 13, the 55 absorbent stirrup 10, is also by preference

of felt. At 11 in the box 2 are drip holes for the escape of lubricant from the box. It will also be noted by comparison of Figures 3 and 5 that the absorbent stirrup 10 is provided with slots 12. The side clamping plates are designated by 13, and each is provided with lower apertures 14 and a pair of upper apertures 15, the lower apertures 14 being provided for the reception of a threaded bolt 16 on which a nut 17 is mounted, and the apertures 15 serving to receive screws 18 which also reach through the upwardly reaching arms of the stirrup 10, as illustrated.

In furtherance of my invention I employ in association with the structure described four metal shims 20, both extremities of each extension end 21 of each shim being slotted, as designated by 22.

It will be noted from the foregoing that in practice all of the bolts of my novel lubricator are rendered taut, and when the cup 4 is filled with fluid grease, fluid graphite or appropriate metal, the lubricant will pass through the apertures 11 of the box 2 and down the sides of the spring, and will penetrate between the leaves of the spring, the latter due to the interposition of the shims in the relation illustrated. It will also be manifest that in virtue of the design of the shims, the lubricant will seep to the under center of each leaf, and hence will lubricate the entire under surface.

The lubricator as shown and described 50 has been reduced to actual practice and successfully used, and experience has demonstrated that one filling of the box 2 will last about seven weeks.

Incident to the use of my novel lubricator each leaf is lubricated from the center to the edges thereof, and there is no objectionable running of lubricant along the sides of the spring or dripping of lubricant from the spring.

The screws 18 are passed through the upturned slotted ends of the shims, as illustrated.

I have entered into a detailed description of the construction and relative arrangement of parts embraced in the present and preferred embodiment of my invention in order to impart a full, clear and exact understanding of the said embodiment. I do not desire, however, to be understood as 105 confining myself to the said specific construction and relative arrangement of parts,

inasmuch as in the future practice of the invention such changes or modifications may be made as fairly fall within the scope of my invention as defined by my appended 5 claims.

Having thus described the invention, what I claim as new and desire to secure by Letters Patent is:—

1. The combination in a vehicle spring 10 lubricator, of a lubricant receptacle adapted to be arranged in superimposed position on a leaf spring, said receptacle having drip apertures, a bottom plate for arrangement below a leaf spring, means connecting the 15 receptacle and the said bottom plate, side clamping plates extending through slots in the bottom plate, means connecting the pendant portions of said side clamping plates, a stirrup of absorbent material ar- 20 ranged above the bottom plate and having upwardly reaching arms with openings therein, means connecting the side clamping plates and said arms of the absorbent stir- rup to the receptacle, and shims associated

with the lubricant receptacle and interposed 25 between the leaves of the spring.

2. The combination in a vehicle spring lubricator, of a lubricant receptacle adapted to be arranged in superimposed position on a leaf spring, said receptacle having drip 30 apertures, a bottom plate for arrangement below a leaf spring, means connecting the receptacle and the said bottom plate, side clamping plates extending through slots in the bottom plate, means connecting the 35 pendant portions of said side clamping plates, a stirrup of absorbent material ar- ranged above the bottom plate and having upwardly reaching arms with openings therein, means connecting the side clamping 40 plates and said arms of the absorbent stir- rup to the receptacle, said means being in the form of bolts or screws, and shims in- terposed between leaves of the spring and having slotted extensions receiving in their 45 slots the said bolts or screws.

In testimony whereof I affix my signature.
JOSEPH J. O'BRIEN.
